(57) **CLAIM**

The ornamental design for a plate for a vehicle canopy or the like as shown and described.

DESCRIPTION

FIG. 1 is a perspective view of a plate for a vehicle canopy or the like showing my new design;

FIG. 2 is another perspective view thereof;

FIG. 3 is yet another perspective view thereof;

FIG. 4 is yet another perspective view thereof;

FIG. 5 is a top plan view thereof;

FIG. 6 is a bottom plan view thereof;

FIG. 7 is a first end elevation view thereof;

FIG. 8 is a second end elevation view thereof;

FIG. 9 is a first side elevation view thereof;

FIG. 10 is second side elevation view thereof;

FIG. 11 is yet another perspective view thereof; and,

FIG. 12 is yet another perspective view thereof.

The dash-dot-dash broken lines illustrate features of the plate for a vehicle canopy or the like that form no part of the claimed design. The short dashed broken lines define bounds of the design and also form no part of the claimed design.
